UNITED STATES PATENT OFFICE.

HERBERT E. METCALF, OF OAKLAND, CALIFORNIA, ASSIGNOR TO THE MAGNAVOX COMPANY, OF OAKLAND, CALIFORNIA, A CORPORATION OF ARIZONA.

METHOD OF EXHAUSTING THERMIONIC TUBES AND LIKE DEVICES.

No. Drawing.

Application filed January 31, 1927. Serial No. 165,045.

This invention relates to a method of exhausting thermionic tubes and other devices and more particularly to the elimination of gas from the filament.

5 The usual method of eliminating gas from the filament device is to burn the filament at a small over-voltage during the exhausting process usually at the last moment, as the gas eliminated at that period may thereby

10 be pumped out.

Great difficulty is experienced in pumping out or removing small amounts of gas thus evolved. The final exhausting of a thermionic device often includes the vaporization of calcium or magnesium to absorb 15 or clean up residual gases. These materials are commonly referred to as a "getter" and may be vaporized by two usual methods: 1st—by heating the "getter" by means of an 20 eddy current heating device or second by using the "getter" as an anode and lighting the filament, thus heating by bombardment.

In the first method employed, the filament may be lit either before or after vaporization. 25 If before, the residual gas may be removed by the "getter" but a coating of the "getter" is left on the filament which is very detrimental to most filaments, particularly to the oxide coated type or any such 30 filaments which depend on oxides for emission. If the filament is burned after the "getter" is vaporized, the gas thrown out is not well absorbed. In the second-named method where the filament is used as a cathode to vaporize the "getter" by bombardment, it suffers greatly from the action of the 35 residual gas and gas evolved from the filament merely adds to this detrimental action.

I have found that residual gas in the filament is promptly and quickly absorbed if 40 that gas is released from the filament during vaporization and deposition of the "getter" on the walls of the tube, and in that manner none of the "getter" metallic or otherwise 45 is left on the filament. The object of the present invention is, accordingly, first that of speeding up the last step of the exhausting operation and secondly to make sure that the gas eliminated from the filament is 50 thoroughly absorbed.

My improved method briefly stated, consists in depositing a "getter" on the plates of the tube, heating the plates with an eddy current device or other means until the 55 "getter" commences to evaporate, immedi-

ately lighting the filament to a high brilliancy and cutting off the current to the eddy current device the moment the filament is lighted, as the radiant heat of the filament is then sufficient to continue the evaporation 60 of the "getter." The filament is permitted to remain lit until the "getter" is entirely spread and the gases emitted completely absorbed.

In actual practice, after the filament, the 65 grate and plates have been assembled, a small amount of "getter" is deposited on the plates. The assembly is then enclosed in the tube in the usual manner and connected with the exhausting pump. When a predetermined 70 vacuum or degree of exhaustion is obtained the eddy current device is applied and the plate is heated to a substantially red heat when vaporization of the "getter" 75 commences. The plate heating device and the filament lighting device are preferably operated from a single handle quick throw switch so that the moment the plate reaches vaporization temperature, the current may be switched from the eddy current device to 80 the filament without appreciable loss of time. The radiant heat of the filament is then sufficient to continue and complete vaporization. Gas is eliminated from the filament during 85 the actual vaporization and deposition of the "getter" and the gas is immediately absorbed by the "getter" no bombardment of any kind takes place in the tube and deposition of the "getter" on the filament is avoided. It is 90 of considerable importance that the filament should not be lit during the time period that the eddy current heating device is employed. Such gas evolved from the filament ionizes due to the voltage employed on the eddy current coils and as such would defeat the 95 purpose, to-wit: that of thoroughly eliminating gas from the filament without any ionization bombardment whatsoever.

The operation of finally removing the 100 gases eliminated by the filament and thoroughly absorbing the same is thus quickly and efficiently accomplished and the tube may finally be sealed in the usual manner.

Having thus described my invention, what I claim and desire to secure by Letters 105 Patent is:—

1. A method of absorbing gas from the filament, of a thermionic device which consists in heating a "getter" material within the thermionic device to a sufficient tempera- 110

ture to start vaporization, discontinuing said operation and immediately burning the filament so as to continue evaporation of the "getter" by means of radiant heat of the 5 filament.

2. In a thermionic device including a plate and a filament, a method of absorbing gas eliminated by the filament, which consists in placing a small amount of "getter" on the 10 plate, heating the plate to start vaporization, discontinuing said heating, the moment vaporization commences and then burning the filament to eliminate the gas contained therein and to complete vaporization of the 15 "getter" by radiant heat from the filament.

3. In a thermionic device having a cathode and a cooperating electrode on which is deposited a material capable of being vaporized, a method of absorbing gas eliminated 20 by the filament which consists in heating the material by an eddy current device until a

sufficient temperature is obtained to start vaporization, discontinuing heating by the eddy current device the moment vaporization commences and then completing vaporization by immediately burning the filament at an over-voltage, so that vaporization may be completed by radiant heat from the filament. 25

4. In a thermionic device having a filament and a cooperating electrode, a method of absorbing gas eliminated by the filament which consists in placing a piece of magnesium or other evaporating "getter" material on the electrode, heating the electrode 30 to start vaporization, discontinuing the heater the moment vaporization commences, then immediately lighting the filament so that the radiant heat will continue vaporization and continuing the burning of the filament until vaporization stops. 40
